US0D1034503S

(12) **United States Design Patent** (10) **Patent No.:** **US D1,034,503 S**
(45) **Date of Patent:** **** Jul. 9, 2024**

(54) **FM TRANSMITTER**

(71) Applicant: **Xiuying Li**, Lichuan (CN)

(72) Inventor: **Xiuying Li**, Lichuan (CN)

(73) Assignee: **Xiuying Li**, Lichuan (CN)

(**) Term: **15 Years**

(21) Appl. No.: **29/927,651**

(22) Filed: **Feb. 5, 2024**

(30) **Foreign Application Priority Data**

Dec. 22, 2023 (CN) 202330846424.X

(57) **CLAIM**

The ornamental design for an FM transmitter, as shown and described.

DESCRIPTION

FIG. 1 is a front perspective view of an FM transmitter, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the FM transmitter, which form no part of the claimed design.

1 Claim, 8 Drawing Sheets
